(57) **CLAIM**

The ornamental design for an SMD LED light strip, as shown and described.

DESCRIPTION

FIG. 1 is a front perspective view of an SMD LED light strip showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

FIG. 8 is an enlarged view of the annotated area shown in FIG. 2; and,

FIG. 9 is an enlarged view of the annotated area shown in FIG. 6.

In the drawings, the broken lines in FIGS. 2, 6, 8, and 9 are for annotating a boundary of the enlarged views and form no part of the claimed design.

1 Claim, 5 Drawing Sheets
